United States Patent

Des. 239,455

Patented Apr. 6, 1976

239,455

SKI

Rudolf Ferch, Salzburg, Austria, assignor to
Kastle G.m.b.H., Ried im Innkreis, Austria

Filed Apr. 23, 1974, Ser. No. 463,375

Claims priority, application Austria Oct. 24, 1973

Term of patent 14 years

Int. CL D21—02

U.S. CL. D34—14 D

FIG. 1 is a top plan view of a ski showing my new design;

FIG. 2 is a side elevational view thereof, the side opposite being substantially identical;

FIG. 3 is a bottom plan view thereof;

FIG. 4 is a front elevational view thereof; and

FIG. 5 is a rear elevational view thereof.

I claim:

The ornamental design for a ski, substantially as shown and described.
